US00D895486S

(12) **United States Design Patent** (10) Patent No.: **US D895,486 S**
(45) Date of Patent: ** Sep. 8, 2020

(54) **MOTORCYCLE**

(71) Applicant: **Harley-Davidson Motor Company Group, LLC**, Milwaukee, WI (US)

(72) Inventors: **Ben McGinley**, Glendale, WI (US); **Brad Richards**, Grafton, WI (US); **Kirk Rasmussen**, Springville, UT (US); **Sean M. Stanley**, Hartford, WI (US); **Brian Scherbarth**, Menomonee Falls, WI (US); **Joseph Konshak**, Sussex, WI (US); **Eric James Klumpp**, Grafton, WI (US); **Curt Zackiewicz**, Milwaukee, WI (US); **David Isaac Aunkst**, St. Francis, WI (US); **Kasey Alexander Peck**, Menomonee Falls, WI (US); **Richard W. Elchert**, Mequon, WI (US)

(73) Assignee: **Harley-Davidson Motor Company Group, LLC**, Milwaukee, WI (US)

(**) Term: **15 Years**

(21) Appl. No.: **29/658,226**

(22) Filed: **Jul. 30, 2018**

(51) LOC (12) Cl. **12-11**

(52) U.S. Cl.

USPC **D12/110**

(57) **CLAIM**

We claim the ornamental design for a motorcycle, as shown and described.

DESCRIPTION

FIG. 1 is a front and right side perspective view of a motorcycle showing our new design;
FIG. 2 is a rear and right side perspective view thereof;
FIG. 3 is a front elevation view thereof;
FIG. 4 is a rear elevation view thereof;
FIG. 5 is a right side elevation view thereof;
FIG. 6 is a left side elevation view thereof; and,
FIG. 7 is a top plan view thereof.

1 Claim, 7 Drawing Sheets
